US00D747029S

(12) **United States Design Patent**
Reynolds

(10) **Patent No.:** **US D747,029 S**
(45) **Date of Patent:** **** Jan. 5, 2016**

(54) **HORTICULTURE GROW LIGHT**

(71) Applicant: **IP Holdings, LLC**, Vancouver, WA (US)

(72) Inventor: **Chris Reynolds**, Vancouver, WA (US)

(73) Assignee: **IP Holdings, LLC**, Vancouver, WA (US)

(**) Term: **14 Years**

(21) Appl. No.: **29/506,973**

(22) Filed: **Oct. 22, 2014**

(51) **LOC (10) Cl.** **26-99**

(52) **U.S. Cl.**

(57) **CLAIM**

The ornamental design for a horticulture grow light, as shown and described.

DESCRIPTION

FIG. 1 is a perspective view of a horticulture grow light, as viewed from below, showing my new design;

FIG. 2 is a perspective view of the light shown in FIG. 1, as viewed from above;

FIG. 3 is a left side view of the light shown in FIG. 1;

FIG. 4 is a right side view of the light shown in FIG. 1;

FIG. 5 is a front elevation view of the light shown in FIG. 1;

FIG. 6 is a rear elevation view of the light shown in FIG. 1;

FIG. 7 is a top plan view of the light shown in FIG. 1; and,

FIG. 8 is a bottom plan view of the light shown in FIG. 1.

The broken-line disclosure shown in the views is understood to represent portions of the article in which the claimed design is embodied, but which form no part of the claimed design.

1 Claim, 7 Drawing Sheets
